UNITED STATES PATENT OFFICE.

ADOLPH G. KAUFMAN, OF NEW YORK, N. Y.

EXTERNAL HOT-BLAST BURNER.

Application filed April 7, 1923. Serial No. 630,531.

To all whom it may concern:

Be it known that I, ADOLPH G. KAUFMAN, citizen of the United States, and resident of New York, in the county of New York and State of New York, have invented certain new and useful Improvements in External Hot-Blast Burners, of which the following is a specification.

This invention relates to improvements in fuel oil gas generators and burners, and particularly to such as are adapted to use low grade oils in an effective manner.

One of the objects of the invention is to provide a burner having a preheating chamber in which the fuel oils are brought to a high temperature before entering the combustion chamber and so arranged that all parts can be readily cleaned should occasion occur.

Another purpose is to produce a burner provided with air regulating shutters to control the combustion of the gases so as to avoid collection of carbon, prevent odor, smoke or flame issuing from the furnace, and eliminate danger of fire by reason of enclosing the flames entirely within the furnace.

Still another object is to provide a burner housing that can be placed in the fuel opening of a common furnace, receptive of a generator or heating unit in such manner that the same can be readily removed from the interior without dismantling the housing or the furnace.

A further aim is in the provision of means whereby the heat from an open fire box or trough can be directed to both the expansion, primary and preheating chamber in starting operations and afterwards closed from the latter chambers at will.

Another aim is to provide means for ejecting and burning any condensed fuel that may collect in the expansion chamber.

These several objects are accomplished by the novel construction and combination of parts hereafter described and illustrated in the accompanying drawing, forming part hereof, and in which:—

Figure 1 is a transverse sectional view of an apparatus made in accordance with the invention.

Figure 2 is a side view thereof.

Figure 3 is a bottom plan view of the same.

Figure 4 is a fragmentary top plan view of the main elements of the burner unit.

Figure 5 is a transverse sectional view taken on line 5—5 of Figure 4.

In the several views the wall of a furnace is designated by the numeral 10, the same having the usual fuel opening 11 into which in carrying out the invention, is projected a hollow casing or housing 12, the same being suited in cross section to the opening 11.

The inner or entering end of the casing is fully open, its edge being in a vertical plane parallel to the furnace wall.

The outer side walls of the casing extend downwardly from the top to the lower front portion which is open to the atmosphere and also along the sides as at 13, these openings for the greater portion of its length extending rearward of the furnace wall, and open at the bottom as at 13', exteriorly the furnace, this opening being covered with gauze if preferred.

Thus the entire outer end of the casing is open except for shutters 14 and 15, respectively upper and lower, fixed on spindles 16 and 17 which extend through the side walls of the casing and are provided with operating handles 18 and 19 and have attached rigid ratchet wheels 20 and 21, each having co-operating pawls 22 and 23 whereby the shutters may be held in adjustment to wholly or partially close the front of the casing.

The upper shutter 14 has a forwardly extending flange 14', the same co-operating with an inwardly extending, curved flange 15' extending at a right angle from the top, axial portion of the shutter 15, thus providing means for effectively controlling the draft and preventing any possible passage of flame outwardly.

The open lower front portion of the casing is covered at its sides by a pair of plates 24, held in position by lugs 25 registering with similar lugs 26 integral with the sides of the casing, and held by a screw or pin 27, in such manner as to permit their withdrawal, these plates completing the side walls of the housing outside the furnace, and it may be noted that the interior of the casing may be lined with fire brick, clay or the like if desired.

Disposed between said plates 24 is a burner device of integral construction comprised of a tubular preheating chamber 28 communicating at its center by a hollow connection 29 with the expansion chamber 30, the latter being in a slightly lower place

and to the front, both chambers being open at each end, their full area and normally closed by suitable sheet packings 31 interposed between their ends and the inner surfaces of the plates 24.

5 In front of the expansion chamber 30 is a trough 32 containing a fibrous substance 33, as asbestos, acting as a wick in igniting the gas.

10 The upper edge of the trough is slightly above the center of the tubular expansion chamber 30 and entering the outer wall of the trough is an overflow pipe 34 leading outwardly of the apparatus.

15 A fuel inlet pipe 35 enters a primary heating chamber 36 below the preheating chamber 28, and communicates with it by the connections 37, provided with removable plugs 38, similar to the plug 39 in the chamber 28 registering with the connection 29.

20 Between the chambers 28 and 30, over the primary chamber 36, are flaps or plate dampers 40 hinged at 41 at their outer ends and provided with eyes 42 by which they may be raised in accordance with the draft desired.

25 Screws 43, passing through the plates 24 into connections 48 between the chambers at their ends maintain the burner members in assembled position, ensure their ends fit tightly against the packings 31, and constitute a complete generation or heating unit.

30 A plurality of perforations 44 are formed at spaced intervals in a row on the uppermost part of the expansion chamber 30 and extending into the chamber is a nipple 45 slanting rearwardly at its outer end so that when the fuel sprays through, it is ignited from the burner perforations and directs the flames inwardly of the furnace.

35 The nipple provides means for ejecting any liquid fuel from the expansion chamber 30, such as may be caused by an excess of oil entering temporarily therein, by condensation or other reasons, raising the liquid and condensate which is received upon the damper plates 40, where it is ignited and consumed, this construction avoiding issuance of fuel, odor, smoke or flame from the furnace.

40 It is to be noted that the plugs 38 and 39 provide access to the interior of the tubes 28 and 36, and by reason of the bolted construction employed, as indicated at 27 and 43 the entire generator or heating unit can be detached for such purposes as may be desired.

45 Having thus described my invention and set forth the manner of its construction, application and use, what I claim as new and desire to secure by Letters Patent, is:—

50 1. In combination with a furnace, an open ended casing disposed in the wall of said furnace, independently operable shutters at

55 the front of said casing, means for maintaining said shutters in adjustment, a combined oil gas generator and burner removably engaged in said casing, a wick carrying trough integral therewith, and dampers 70 operable to control heat from said trough to said generator elements.

60 2. The combination with an oil fuel heating unit of a condensation nipple adapted to eject condensation fuel whereby said condensation is ignited and consumed.

65 3. The combination with an oil fuel heating unit of a condensation nipple directed inwardly of the furnace and adapted to eject condensation fuel whereby said condensation is ignited and consumed.

70 4. The combination with a furnace, a casing extending partially through the wall thereof, a frame removably engaged in the lower front part of said casing, a primary 85 heating chamber, a secondary heating chamber, an expansion chamber and an igniting trough, all of said elements being integrally combined, open at their ends and held between the sides of said frame, connections 80 between the several chambers, and supply means entering the primary heating chamber.

75 5. A combined fuel oil gas generator and burner comprising a unitary structure having a tubular primary heating chamber into which oil is fed, a secondary heating chamber communicating at spaced intervals with said primary chamber, an expansion chamber having a single tubular connection with 100 said secondary chamber, all of said chambers being arranged in spaced substantially parallel relation and open at their ends, an igniting trough formed alongside said expansion chamber receptive of fuel therefrom, plates rigidly secured at the ends of said chambers, and gaskets interposed between said plates and chamber ends.

80 6. A combined fuel oil gas generator and burner comprising a unitary structure having a tubular primary heating chamber into which oil is fed, a secondary heating chamber communicating at spaced intervals with said primary chamber, an expansion chamber having a single tubular connection with 110 said secondary chamber, all of said chambers being arranged in spaced relation and open at their ends, plates removably engaged at the ends of said chambers, a condensation nipple extending through the wall of said expansion chamber, said chamber having perforations in its upper wall, means for igniting gases issuing from said nipple and perforations, and means permitting access to the connections between said chambers.

85 7. A combined fuel oil gas generator and burner, a unitary structure having a tubular primary heating chamber into which oil is fed, a secondary heating chamber communi- 120

cating at spaced intervals with said primary chamber, an expansion chamber having a single tubular connection with said secondary chamber, all of said chambers being arranged in spaced parallel relation, shutter plates hingedly arranged to cover the space between said secondary and expansion chambers, removable plugs in the connections between said chambers, and an elongated wick carrying fire box disposed adjacent discharge openings in said expansion chamber.

8. A combined fuel oil gas generator and burner comprising a unitary structure having a plurality of preheating chambers, an expansion chamber containing perfor-

rations, a nipple in said expansion chamber, said nipple extending nearly to its bottom and outward at a rearwardly inclined angle, a wick containing fuel trough adjacent said expansion chamber receptive of fuel from the perforations in said chamber in the initial stage of operation, means for controlling the heat delivered to said preheating chambers, removable closures at the ends of said chambers, tubular connections between said chambers, and removable plugs in said connections permitting entry thereto.

Signed at New York, in the county of New York and State of New York, this 27th day of March A. D. 1923.

ADOLPH G. KAUFMAN.
